Primary Examiner — Philip S Hyder*Assistant Examiner* — Ryan Harvey(74) Attorney, Agent, or Firm — Duane C. Basch; Basch & Nickerson LLP(57) CLAIM

I claim the ornamental design for a top surface of a gaming table, as shown and described.

DESCRIPTION

The FIGURE is a top plan view of the top surface of a gaming table showing my new design.

The broken line showing of portions of the top surface of a gaming table depicts environment and forms no part of the claim.
